CORNER CONSTRUCTION

Walter M. Krantz, Youngstown, Ohio, assignor,
by direct and mesne assignments, to Ace Storm
Window Company, Youngstown, Ohio, a cor-
poration of Ohio

Application December 15, 1944, Serial No. 568,349

3 Claims. (Cl. 189—76)

This invention relates to a corner construction by means of which unitary frame-like structures can be formed simply and efficiently.

The principal object of the invention is the provision of a corner construction particularly adapted for constructing frame-like structures.

A further object of the invention is the provision of a corner construction comprising means for uniting pre-cut mitered sections of frame material.

A still further object of the invention is the provision of a framing section and a corner piece adapted to unite pieces of the framing section in an efficient corner construction.

The corner construction shown and described herein has been designed to facilitate the construction of frames such as may be employed for various purposes including the formation of storm sash and the like. It is well known that in the formation of various types and sizes of frames such as are employed for storm sash purposes the ability to form a tight and structurally sound corner construction is highly advantageous to the simple and inexpensive frame construction. The particular corner construction shown and described herein enables the ready formation of rectangular frames by the simple expedient of cutting pieces of the frame section of suitable length, mitering the ends and uniting the cut pieces into a frame structure by the application to the corners thereof of L-shaped brackets so formed as to tightly hold the corners of the frame formed in desired relation to one another. As used in forming storm sash the corner construction shown and described herein permits the ready assembly of storm sash in a manner to provide for the positive fit of the completed sash with respect to the window opening for which it is intended.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein:

Figure 1 is a top plan view of the improved corner construction.

Figure 2 is a view of the frame sections of the corner construction with the bracket portion removed.

Figure 3 is a cross sectional end elevation of the bracket portion of the corner construction.

Figure 4 is a cross sectional elevation of the corner construction taken on lines 4—4 of Figure 1.

Figure 5 is a cross sectional elevation of the corner construction taken on lines 5—5 of Figure 2.

Figure 6 is a perspective elevation of one of the locking keys employed in assembling the corner construction.

Figure 7 is an enlarged cross sectional end elevation of the frame and corner piece showing the keys used in locking the sections together and illustrating the provision made for altering the plane of the frame section of the corner construction with respect to the bracket portion thereof.

Figure 8 is a perspective elevation of a shim as used in Figure 7 for altering the plane of the frame portion of the corner construction.

By referring to the drawing and Figures 1 and 2 in particular, it will be observed that a corner construction capable of being employed for many uses has been illustrated as applied to the formation of right angle corners such as would be found in storm sash construction in forming a rectangular frame to fit a dwelling window opening. In Figure 1 a side frame section 10 is shown united to a top frame section 11 at their mitered corners 10A and 11A, respectively, by means of an L-shaped bracket 12. In Figure 2 a comparable corner between the top frame section 11 and another side frame section 13 is illustrated, the sections 11 and 13 being in engagement at their mitered ends 11B and 13A.

By referring to Figure 5 of the drawing the cross sectional form of the side frame section 13 may be seen to comprise an inverted T-like section including an inwardly extending flange 13B and an outwardly extending flange 13C, the main section 13 of the frame also being provided with oppositely disposed stub-like flanges 13D.

The shape of the frame section 13, which is exactly the same as the shape of the frame sections 10 and 11 illustrated in Figures 1 and 2, provides in effect a pair of oppositely disposed, axially extending channels 13E on the sides of the frame section 13, which channels 13E in conjunction with the corner bracket 12, serve to unite the frame sections 13 and 11 to the corner bracket 12.

By referring to Figure 3 of the drawing a cross sectional end elevation of the corner bracket 12 may be seen and it will be observed that it con-

sists of a general inverted U-shape provided with an inwardly extending flange 12A, the ends of the arms of the inverted U being provided with inwardly turned stub-like flanges 12B.

By referring now to Figure 4 of the drawing it will be observed that when the frame section 10 is united to the frame section 11, as also shown in Figure 1, the ends 10A and 11A of the side section 10 and the top section 11, respectively, are slipped within the channels defined in the bracket 12 and a pair of keys 14 are driven in alongside the frame sections 10 and 11 to positively unite the corner bracket 12 to the frame sections 10 and 11. If desired, drilled and threaded openings may be provided in the frame pieces 10, 11 and 13, as indicated by the numerals 15 in Figure 2, and screws such as indicated by the numerals 16 in Figure 1 may be employed to further unite the corner bracket 12 with the frame sections 10, 11 and 13, respectively.

It will thus be seen that when four frame sections are cut to proper size and provided with mitered ends, four of the corner brackets 12 may be effectively employed to form a square of rectangular frame which may then be used with the full confidence that it will retain its assembled shape as effectively and efficiently as though the corners had been welded to one another.

In the formation of storm sash frames it is, therefore, possible to form any size and shape of storm sash frame from continuous lengths of the primary frame form such as illustrated in Figure 5 and upon cutting appropriately sized lengths for the frame to be formed and mitering the corner the several pieces may be efficiently and simply united into the appropriately sized frame by the simple application of the corner brackets 12 as illustrated and heretofore described. It will be obvious that under most conditions the drilled openings 15 and the screws 16 may be safely dispensed with as the locking keys 14 will unite the corners of the frame sufficiently for their purpose. In forming some frame constructions it may obviously be desired to vary the plane of the frame with respect to the corners so that frames may be formed to more perfectly fit unusually shaped openings. Means is provided for achieving such a result and by referring to Figures 6, 7 and 8 such means may be seen.

In Figure 7 an enlarged cross sectional detail of a corner bracket 17 is illustrated in locked position on an enlarged frame section 18. Downturned arms 17A with their inturned stub flanges 17B form in conjunction with the out-turned stub flanges 18A of the frame section 18 channels for the location of keys 19. By referring to Figure 6 a perspective elevation of one of the keys 19 may be seen. In order that the plane of the surface 18B of the frame section 18 may be varied with respect to the plane of the surface 17B of the

bracket a shim 20 is positioned as shown between one of the downturned arms 17A and the adjacent portion of the frame section 18. In Figure 8 a perspective elevation of one of the shims 20 is illustrated.

In connection with the illustration of Figure 7 it will be observed that the frame section 18 is provided with a pair of upstanding wedges 21 which serve to prevent the sideward spreading of the arms 17A of the corner bracket 17.

It will thus be seen that a simple and efficient corner construction has been illustrated and described which is particularly adapted to the formation of storm sash corners and that the resulting frame and corner combination may be effectively used for the direct mounting of glazed or unglazed shape thereof and that the frame section itself so formed may be mounted directly on or over window openings in a dwelling or other building thereby permitting an all metal storm sash to be simply and effectively constructed. It is obvious that the corner construction is applicable to many other types of framing wherein strong, durable and easily formed corner constructions are advantageous.

Having thus described my invention, what I claim is:

1. In a corner construction for framing members having an upstanding rib, a corner bracket 30 including depending arms adapted to overlie the said upstanding rib of the framing members, and keys positioned between the said upstanding rib of the frame and the said downturned arms of the corner bracket so as to lock the corner bracket to the said framing members.

2. The combination of a framing member comprising a surface flange having an upstanding T-headed body axially formed thereon and means for uniting mitered sections of the said framing members, said means consisting of wedges and 40 L-shaped brackets each comprising a surface flange having depending arms formed thereon, inwardly turned stub flanges formed on the said depending arms of the L-shaped bracket to provide in conjunction with the T-shaped body of the framing section channels for the insertion of the said wedges for locking the assembly together.

3. A storm sash frame comprising framing members having outwardly extending surface flanges and a T-shaped axially extending body section, and means for uniting the framing sections at their mitered corners, said means including L-shaped brackets having downwardly depending arms for engaging the said T-shaped portions of the framing members and means for attaching the L-shaped corner brackets to the said framing members so as to form a corner construction.

WALTER M. KRANTZ.
